TELEPHONE SYSTEM

Application filed May 26, 1928, Serial No. 280,890, and in Germany May 28, 1927.

This invention relates to an arrangement for signaling in telephone systems.

Telephone-service, specially on long lines, is operated with audio-frequency A. C. to produce the signals between exchange and subscriber. This alternating current is transmitted by the amplifiers in the same way as any frequency contained in the speech-waves. In order not to be obliged to alter the calling-devices of the exchanges and subscribers, this current at the input and output of the toll-line is converted into the usual 25-cycle calling-current. Now, as the calling implements of the lines are continuously connected in parallel, they may easily be actuated by the frequencies contained within the speech. This is avoided by chopping or modulating the audio-frequency signalling current into a slow rhythm, and the receiver must be circuited in a way that it responds and transmits the 25-cycle calling current to the subscriber only, when the two selectivity-demands are fulfilled, viz, when a calling-current of exactly defined periodicity (500 cycles) in the period of a second exactly defined frequency (25 cycles) induces the receiver-device to actuate. With the known devices for this purpose one or several tubes are used as amplifiers, rectifiers and several mechanically tuned resonance relays or electrical tuning-means for one of the two frequencies or for both of them.

These devices are very costly and demand a continuous attendance of the service. The present invention removes these disadvantages in a simple and yet safe way as follows. By the interference of the modulated in low-frequency-current or chopped high-frequency-current with a relay working on the principle of an A. C. moving-coil-instrument. A mechanical device is influenced to vibrate in the period of the modulating-frequency, thus causing the actuation of a relay which does the transmission of the call in the lower frequency.

On the drawing attached the object of this invention has been illustrated by an example, and

Fig. 1 is the top-view of the device.
Fig. 2 is the front-view of the device.

On the outer limbs (a) and (b) of a three-limbed laminated magnet (d) of the relay (p) (Fig. 1) two coils (e) and (f) have been fixed. A third coil is fixed on the medium limb (c), which eventually may allow a D. C. superposed magnetization of the core. A frame (h) is fixed in the notches of the pole-pieces, which frame is carried by a steel-reed (i) (Fig. 2), and which is designed to accommodate a number of wire-windings, which will be connected in series with the coils (e) and (f). The steel-reed is clamped into the copperblock (k), and equipped with a sliding weight *m*, by means of which it is possible to adjust this entire system: frame, steel-reed and tuning-weight to an exactly defined mechanical resonance; besides the frame on its upper side, carries a contact-spring (n), which may vibrate between two equal contacts (o). These are fixed to the pole-piece of the middle limb (c).

When transmitting calls in the usual way on toll-cables, the electric system consisting of the coils (e) (f) and the frame-windings, by connection in series with a condenser (C), will be operated with a natural frequency of 500 cycles. Thus the relay connected in parallel with the toll-line (f) takes its highest energy with 500 cycles, as its apparent resistance shows a minimum at this frequency. The alternating current passing the frame creates a declination of the frame which is uni-directed on either side. As soon as the 500-cycles current changes its sense, all magnetic powers reverse their directions, also the frame-current, resulting in the same mechanical declination.

Now, when at an audio-frequency-call this 500 cycle-current is modulated and interrupted in the period of 25 cycles, this current passing the relay exercises the equal mechanical force on the frame 25 times per second. If the entire mechanical vibrating system is tuned on 25 cycles, it will—after a certain lapse of time, say f. i. $1\frac{1}{2}$ —1 second—reach its maximum amplitude of oscillation. In this stage the contact-spring clamped on the frame alternately touches the two flanking springs, and by actuating another relay (which does not appear on the drawing at-

tached) it is possible to call the subscriber by means of the local calling-current supply of 25 cycles.

So, with the help of a single relay, it is reached that a retransmission-call will only occur, when calling-current of exactly the periodicity of 500 cycles with a modulating-frequency of exactly 25 cycles is in action. By the delay of the retransmission-call (1/2 to 1 second) created by the oscillatory start of the tuned reed until contact is reached, the danger of actuation of this device at certain frequencies contained in the language is considerably reduced, as such frequencies usually appear only for moments.

35. What I claim is:

1. An arrangement for signalling in telephone-systems, comprising a relay operated by a current of a high frequency modulated by a lower frequency, and a mechanical device operated by said relay, to vibrate at a period equal to the modulating frequency, said mechanical device consisting of a steel reed,

10 a frame and a block.

25. An arrangement for signalling in telephone-systems, comprising a relay operated by a current of a high frequency modulated by a lower frequency, and a mechanical device operated by said relay, whereby said mechanical device vibrates in period of the modulating frequency, said mechanical device consisting of a steel reed, a frame and a block, said steel reed carrying a sliding weight, whereby said mechanical device obtains a certain swinging movement adapted to the frequency of the modulated current.

30. An arrangement for signalling in telephone-systems, comprising a relay operated by a current of higher frequency modulated by a low frequency, and a mechanical device controlled to vibrate in a period equal to the modulating frequency, said mechanical device consisting of a steel reed, a frame and a block, said steel reed carrying a sliding weight, whereby said mechanical device obtains a certain swinging movement adapted to the frequency of the modulated current, and a contact arranged on the frame controlled by said mechanical device.

35. An arrangement for signalling in telephone-systems, comprising a relay operated by a current of higher frequency modulated in a low frequency, and a mechanical device influenced by said relay, to vibrate at a period equal to the modulating frequency, a relay operated by said mechanical device, for effecting the signalling in the low frequency, said mechanical device consisting of a steel reed, a frame and a block, said steel reed carrying a sliding weight, whereby said mechanical device obtains a certain swinging movement adapted to the frequency of the modulated current, and a contact arranged on the frame controlled by said mechanical device.

40. In a signalling system, an alternating

current relay, a circuit connected to said relay for impressing modulated currents across said relay, a vibrating member controlled by said relay having a natural period of vibration equal to the frequency of the modulating currents and a pair of contacts controlled by said vibrating member.

45. In a signalling system, an alternating current relay, an electric circuit connected to said relay for supplying modulated currents thereto, a vibrating member carried by said relay, said vibrating member having a normal and alternate position and being normally held in a predetermined normal position and responsive when said relay is energized by said modulated currents for operation to its alternate position at a frequency equal to said modulating frequency, and an electric circuit controlled by said vibrating member.

50. In a signalling system, a relay having a first winding, a source of alternating modulated current connected to said first winding for energizing said winding, a second winding, a source of direct current for energizing said second winding, a vibrating member having a predetermined and alternate position, said vibrating member being held in a predetermined normal position by said second energized winding and being operative in response to energization of said first winding by said modulated frequency to move to its alternate position at a frequency equal to the modulated frequency and a pair of contacts controlled by said vibrating member.

55. Means for converting high frequency currents modulated by current variations of lower frequency, into currents of said lower frequency, comprising a relay, a winding of said relay, a moving coil armature for said relay, means to supply both said winding and said moving coil with currents of said modulated high frequency, means to mechanically tune said lower frequency and means to transform the movements of said moving coil into corresponding electrical variations.

60. In testimony whereof I have affixed my signature.

DR. GERHARD GRIMSEN.
